UNITED STATES PATENT OFFICE.

GEORGE F. WOLF, OF BALTIMORE, MARYLAND.

PAPER HOLDER AND CUTTER.

1,270,580.

Specification of Letters Patent. Patented June 25, 1918.

Application filed December 37, 1916. Serial No. 130,127.

To all whom it may concern:

Be it known that I, GEORGE F. WOLF, a citizen of the United States, residing at Baltimore, in the State of Maryland, have invented certain new and useful Improvements in Paper Holders and Cutters, of which the following is a specification.

This invention relates to improvements in paper holders and cutters, and has for its object to provide a cheap, simple and efficient device for holding a roll of wrapping paper and by means of which the paper can be cut the desired length.

The invention consists of the novel construction and arrangement of the parts and combination of parts hereinafter more fully set forth in the following specification and pointed out in detail in the appended claim.

In the accompanying drawings,

Figure 1 is a side elevation of my invention with the hinged cutting edge partly raised.

Fig. 2 is a vertical section of Fig. 1, the hinged cutting edge being lowered.

Fig. 3 is a top plan view.

Referring to the accompanying drawing, forming part of this specification, and in which like reference numerals designate like parts throughout the several views thereof, 30 1 designates the body of the holder having a number of rollers 2 revolvably mounted in opposite sides of said body 1 and, upon which the roll of paper 3 rests, the front and rear rollers being mounted higher than the central rollers. A frame 4 is hinged at 35 5 to the upper edge of the body 1 and has an inclined surface 6 at the front thereof and a cutting blade 7 extending across the front adjacent said inclined surface. Said cutting blade 7 rests on the front of the body 1 just back of the cutting blade 8 which permits of the paper being cut by either an upward or downward movement thereof. The front of the body 1 is also 40 provided with a cutting blade 8 which extends slightly above the front upper edge of the said body 1 and close to the blade 7. A spring 9 extends across the body 1 on the

inside thereof and is detachably connected to the eyes 10.

The roll of paper 3 is placed in the holder 1 and rests on the rollers 2. The end of the paper is drawn under the spring 9 and out over the front of the body 1, and when drawn out to the desired length can be readily cut off by the blade 7 if pulled upwardly or by the blade 8 if pulled downwardly. The spring 9 will hold the end of the paper from folding back upon the roll and when the frame 4 is raised the paper 60 can again be drawn out and cut as described. The inclined surface 6 will prevent the paper catching should there be a tear in same or in the event the paper should be wrinkled as is usually the case when the roll is nearly used.

By my invention the entire roll of paper can be used and the paper can be cut the desired length by the upward or downward movement whichever may be the most convenient. It will also be seen that it is not necessary to fasten the holder and that the same may be placed in any position and moved about at will.

Having thus described my invention, 75 what I claim is:

A paper holder and cutter comprising a body, a cutting blade secured to and extending slightly above the upper front edge of said body, a frame hinged to the upper edge of said body and having an inclined surface at the front thereof, a cutting blade extending across the front of said frame adjacent to the said inclined surface and adapted to rest on the front edge of the body just back of the cutting blade thereon, a spring detachably secured to and extending across the said body back of the cutting blades, and rollers in said body upon which the paper rests.

In testimony whereof I affix my signature in the presence of two witnesses.

GEORGE F. WOLF.

Witnesses:

CHARINA FERGUSON,

THELMA BOWLEY.
